UNITED STATES PATENT OFFICE

2,059,785

AIR-PRESSURE DEVICE

Arnold Gaik, Chicago, Ill.

Application April 29, 1935, Serial No. 18,973

4 Claims. (Cl. 4—255)

This invention relates to an air-pressure device and more particularly to a device adapted to force objects through or out of conduits, drains, etc.

5 An object of the invention is to provide an improved air-pressure device which may be operated with little effort and which provides an exceedingly tight seal with a drain or conduit opening etc. A further object is to provide a 10 portable air-pressure device which may be operated accurately and without danger of the back flow of materials within a drain or other conduit. Other specific objects and advantages will appear as the specification proceeds.

15 The invention is illustrated in a preferred embodiment, by the accompanying drawings, in which—

Figure 1 is a broken longitudinal sectional view showing a device embodying my invention; Fig. 2, 20 a top plan view; Fig. 3, a perspective view of the valve stem and guide, a portion of the outlet pipe being shown in section; Fig. 4, an enlarged detail sectional view showing the lower portion of the apparatus; and Fig. 5, a broken bottom plan 25 view of the device.

In the illustration given, A designates a pressure vessel or chamber; B, a pump; and C, a sealing device.

The pressure chamber or tube A may be of 30 any suitable construction. In the illustration given, the tube A is closed at its upper end except for the central perforation 10 through which extends the valve stem 11. Into the lower end of tube A is threaded an outlet pipe 12 having a portion thereof extending into the 35 interior of the tube and providing a valve seat 13.

The pump B is supported by a strap 14 formed 40 integrally with the tube or casing A. The pump may be of any suitable construction. In view of the fact that the pump is of well known construction, a detailed description is believed unnecessary. A tube 15 connects the bottom of the pump with a side wall of tube A; and a check valve 16 of well known construction permits air 45 to flow from pump B into conduit 15, but prevents the back flow of air. It will be observed that the pump B is supported at a spaced distance from tube A so as to be out of the way when the pressure device is being centered in a 50 drain for operation.

The valve stem 11 is provided with a spring 55 abutment 17 which serves to support a compression spring 18 between it and the top wall of casing A. Above casing A is a threaded extension 19 to which is secured a threaded sleeve 20. Between sleeve 20 and stem 11 is a sealing sleeve 21 of rubber or other suitable material and a clamping nut 22 is threadedly secured to the upper portion of sleeve 20 and serves to compress

and seal the upper portion of the sealing sleeve 21.

A supporting handle 23 is carried by arms 25 secured to the top wall of casing A, the center of the handle 24 being directly above the valve stem 11. The end of the valve stem 11 is provided with a handle 26. It will be observed that the handle 26, when the valve stem is in its lower position, is spaced from the handle 24 at a convenient distance so that the fingers of the operator may readily grasp the handle 26 to draw it toward handle 24. This construction permits accurate control of the valve when the device has been centered properly with respect to the drain. 15

The lower end of valve stem 11 is threaded to engage a valve support 27, a valve 28 of rubber or other suitable material and an interiorly threaded valve guide 29. The valve guide 29 is provided near its lower end with cross flanges 30 20 which are adapted to engage the inner walls of outlet pipe 12, while at the same time permitting air to rush through the outlet pipe when the valve is lifted. The flanges 30 keep the valve stem 11 centered with respect to casing A and outlet 25 pipe 12.

The outlet pipe 12 is provided below the closed end of casing A with a ball-supporting bell 31, the bell being clamped between the threaded collars 32 and 33. 30

The sealing member C preferably comprises a sponge rubber ball having a closed or watertight skin 34. The ball is provided with a small central opening through which the outlet pipe 12 is pressed. The upper portion of the wall is confined within the bell 31. 35

While in the drawings, the ball is shown touching the lower edge of the bell, in actual operation, a substantial portion of the ball is pressed upwardly to fill the concavity of the bell. Should 40 the lower portion of the ball be worn away in actual use and rendered unsatisfactory as a seal, the ball may readily be reversed in position. The contour of the upper side of the ball may be other than spherical and may be of such shape as to 45 render it effective for use with particular types of drains, etc. For example, the upper side of the ball may be substantially concave. The user could then, at his option, use the lower uniformly curved side of the ball, or he could reverse the 50 ball to use the upper side with its particular contour.

In the operation of the device, the pump B is manipulated to fully charge the pressure tube A. The ball C is then placed in an open drain and 55 pressed downwardly therein so as to form a complete seal. When the ball has been centered under heavy pressure and occupies the desired position, the operator draws the valve handle 36 toward the handle 24 upon which his hands are 60

placed in exerting the pressure. The air is released through the raising of valve 28 and passes about the guide flanges 30 and into the drain pipe. The stop 17 prevents the valve from being raised sufficiently high to permit the guide 29 to be drawn out of outlet pipe 12.

If desired, a pressure gauge A' may be connected with the upper portion of casing A, as illustrated more clearly in Fig. 2.

- 10 Air-pressure devices have been used for many years for removing obstructions from drains, etc.; however, such devices have been difficult to operate with accuracy and in their operation, have frequently allowed liquids and materials in the drain pipe to be forced backwardly around the sealing member and into the room. Rubber cups, disks, etc. have been found unsatisfactory because if they are made sufficiently stiff to resist the pressure, they do not form a sufficiently tight seal.
- 15 The sealing ball C yields sufficiently under high pressure to adapt itself to every slight contour of the drain edge or surface while at the same time, in its compressed form, it is sufficiently rigid to resist any back pressure. By employing a valve construction of the type shown and in which the operator may grasp the valve handle while pressing upon handle 24, the discharge of air can be accurately controlled and properly timed with the centering of the sealing ball C. The device
- 20 can be handled with speed and with ease.
- 25
- 30

While in the foregoing description, I have set forth a specific construction as an illustration of the principles of my invention, it will be understood that variations may be made therefrom

without departing from the spirit of my invention. The foregoing detailed description has been given for clearness of understanding only, and no unnecessary limitations should be understood therefrom, but the appended claims should be construed as broadly as permissible, in view of the prior art. 5

I claim:

1. In combination with an outlet pipe, a rubber ball centrally perforated and adapted to tightly 10 receive the terminal portion of said pipe, and bracing means associated with said pipe and engaging the rear portion of said ball.
2. In combination with an outlet pipe, a sponge rubber ball perforated centrally to receive said 15 outlet pipe and having an air-tight skin, and a bell support associated with said pipe and engaging the rear portion of said ball.
3. In combination, an outlet pipe, handle means for exerting pressure on said outlet pipe, a resilient sealing ball centrally apertured to receive 20 said outlet pipe, and brace means carried by said pipe and engaging the rear portion of said ball.
4. In combination with an outlet pipe, a pressure container communicating with said pipe, a manually operable valve controlling the flow 25 from said container to said outlet pipe, and means for supplying a gaseous material under pressure to said container, a rubber ball provided with an opening extending through and adapted to receive a portion of said outlet pipe, and bracing means associated with said pipe and engaging the rear portion of said ball. 30

ARNOLD GAIK.
